(57) **CLAIM**

The ornamental design for an electronic copying machine, as shown and described.

DESCRIPTION

FIG. 1 is a front view of an electronic copying machine showing a first embodiment of our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof;

FIG. 8 is a front view thereof, shown with the coloration omitted for ease of disclosure;

FIG. 9 is a rear view thereof, shown with the coloration omitted for ease of disclosure;

FIG. 10 is a top plan view thereof, shown with the coloration omitted for ease of disclosure;

FIG. 11 is a bottom plan view thereof, shown with the coloration omitted for ease of disclosure;

FIG. 12 is a right side view thereof, shown with the coloration omitted for ease of disclosure;

FIG. 13 is a left side view thereof, shown with the coloration omitted for ease of disclosure;

FIG. 14 is a perspective view thereof, shown with the coloration omitted for ease of disclosure;

FIG. 15 is a front view of an electronic copying machine showing a second embodiment of our new design;

FIG. 16 is a rear view thereof;

FIG. 17 is a top plan view thereof;

FIG. 18 is a bottom plan view thereof;

FIG. 19 is a right side view thereof;

FIG. 20 is a left side view thereof; and,

FIG. 21 is a perspective view thereof.

The broken line showing illustrates portions of the electronic copying machine which do not form a part of the claimed design.
